MULTIPLE TUBE GAS TRIODE INVERTER

Charles C. Shumard, Moorestown, N. J., assignor
to Radio Corporation of America, a corporation
of Delaware

Application February 27, 1948, Serial No. 11,811

1 Claim. (Cl. 321—36)

1

This invention relates to improvements in electronic apparatus for inverting direct current into alternating current. More particularly, it relates to improved apparatus and methods for performing the inversion at high audio frequencies.

Although apparatus utilizing gas discharge tubes has been previously devised for changing D.-C. to A.-C., this has generally been limited to frequencies of the order of a few hundred cycles per second and has been able to handle only low currents at relatively high audio frequencies. By utilizing the apparatus and methods of the present invention, alternating current outputs of 20,000 cycles and beyond may be accomplished using well designed tubes. Power output can be 5 kw. or better.

In general, the improvements of the present invention are brought about by using two or more pairs of gas discharge tubes. Each pair of tubes charges and discharges a separate capacitor connected in interrelated anode to cathode circuits of the tubes and the outputs of these circuits are coupled to the load. The tubes are fired in an order such that each tube has time to deionize sufficiently before being readied to fire again and is maintained in such condition that it cannot fire prematurely while undergoing deionization.

The principal object of the present invention is to provide an improved method and apparatus for inverting direct current to alternating current, using at least four gas discharge tubes.

Another object is to provide improved means for inverting high amperage direct current to alternating current at high efficiencies.

Another object is to provide apparatus for inverting direct current to alternating current in which the efficiency of gas discharge tubes having a certain deionization time is increased.

Still another object of the present invention is to provide apparatus for inverting direct to alternating current in which at least four gas discharge tubes are used but in which the power rating of each tube may be correspondingly lower than in a circuit utilizing two tubes.

These and other objects will be more readily apparent and the invention will be better understood from the following specification taken in connection with the drawings, of which:

Fig. 1 is a schematic diagram of a circuit representing one embodiment of the present invention.

Fig. 2 is a graph showing voltage wave forms in different parts of the circuit of Fig. 1, and

Fig. 3 is a schematic diagram of a circuit of another embodiment of the present invention.

2

Referring to the embodiment illustrated in Fig. 1, a pair of gas discharge triode tubes 1 and 3 and a similar pair of tubes 2 and 4 are each provided with similar external grid circuits and similar external anode to cathode circuits. Tube 1 of one pair and corresponding tube 2 of the other pair are each provided with similar grid bias supplies 5 and 6, respectively, which normally furnish a negative bias to the grids of the tubes. Tubes 3 and 4, the other corresponding tubes of each pair, are provided with a common grid bias supply 7 similar to bias supplies 5 and 6 for furnishing normally negative bias to the grids of these tubes. However, the positive side of this common bias supply is grounded. This is in contrast to the other two which are isolated from ground.

Similar grid current limiting resistors 8, 9, 10 and 11 are provided in the grid circuits of the tubes 1, 2, 3 and 4, respectively.

The output of a pulser timing unit (not shown) is connected to the grid of each tube through the transformers 12, 13, 14 and 15, respectively. This pulser timing unit may be of any suitable conventional type such as shown in United States Patent 2,146,862 and the operation is as shown and described in co-pending application, Serial No. 725,249, filed January 30, 1947.

The cathodes of each of the tubes 1 and 2 are connected to the positive side of the grid bias supplies 5 and 6, respectively. The cathodes of each of the tubes 3 and 4 are connected to ground.

In the anode to cathode output circuits of tubes 1 and 3 is a common capacitor 16. Similarly, for the other pair of tubes 2 and 4, there is provided a like capacitor 17. The anode to cathode circuit path of tube 1 comprises an inductor 18, the "B" supply 22 and through ground to the capacitor 16, primary 23 of a loading transformer 21 and thence to the cathode.

The anode to cathode circuit path of tube 3 comprises an inductor 20, the primary winding 25 of loading transformer 27, the capacitor 16 and thence through ground to the cathode.

The first tube 2 of the second pair has an external anode to cathode circuit path exactly similar to the corresponding tube 1 of the first pair. It includes an inductor 19, the "B" supply 22, and through ground to the second capacitor 17, through the primary winding 24 of loading transformer 27 and thence to the cathode.

The anode to cathode circuit path of tube 4 is exactly like that of corresponding tube 3 of the first pair. It comprises an inductor 21, the primary winding 26 of the loading transformer and

through the capacitor 17 to the grounded cathode.

The direct current source or "B" supply 22, which is to have its output inverted to A.-C., has its positive side connected to the anodes of both tubes 1 and 2 through the inductors 18 and 19 while its negative side is grounded.

As previously noted, a primary winding of loading transformer 27 is included in the anode to cathode circuit of each tube. These windings are all in the same direction, with the connections as illustrated, and provide coupling between the circuits. The transformer is provided with a common secondary winding 28 which in turn is connected to the load as represented by load resistor 29.

The manner in which this circuit operates in inverting D.-C. from the "B" supply 22 to A.-C. will now be described in more detail. Let it be assumed, at first, that all of the gas discharge tubes are non-conducting but heated and ready for conduction. Let tube 1 be triggered by the signal supplied from the pulser-timing unit through transformer 12. This is accomplished by momentarily making the grid more positive than the cathode. Tube 1 will now conduct and capacitor 16 will be charged from the "B" supply through the inductor 18 and the primary winding 23 of transformer 21. Since no other circuit paths are available at the instant, capacitor 16 will charge to a voltage depending on the constants of the circuit. In such an oscillatory circuit having L, C and R in series with a suddenly applied voltage E, the maximum voltage $e_{c_{max}}$ across the capacitor, if no original charge was on it, rises to a value—

$$e_{c_{max}} = E(1 + e^{-\alpha\tau})$$

where

$$a = \frac{\alpha}{\omega}, \alpha = \frac{R}{L}, \omega = \sqrt{\omega_0^2 - \alpha^2}$$

$$\omega_0 = \frac{1}{LC}, \text{ and } e = 2.72 +$$

If $a=0$, corresponding to zero resistance, the voltage will rise to a value of $2E$, the theoretical but practically unobtainable maximum value.

The capacitor would then start to discharge causing current to flow in the opposite direction but since the discharge tube conducts in only one direction, the capacitor cannot discharge and is left charged to a certain degree.

Since the current cannot reverse its direction through the discharge tube, this tube will now start to deionize. The deionization process normally takes an appreciable interval of time but may be hastened. The slower-moving positive ions may be attracted more rapidly to the grid if the high negative bias is immediately returned to this element after the tube is fired. The time constant of the grid circuit likewise should be made as low as feasible; hence, the value of the resistor 8 should be kept low and the leakage reactance of the transformer 12 small. It is preferable to use a regulated grid bias supply. The resistance 8 may be made small although it is desirable to limit grid current flow while the tube is conducting.

In order to provide more deionization time and thereby increase the frequency of operation, while tube 1 is deionizing, the corresponding tube 2 of the second pair is triggered through its pulsing transformer 13. This charges the second capacitor 17, which is preferably equal in value to capacitor 16, through current flowing in the

tube 2, inductor 19 and primary winding 24 of transformer 21. The current in the load resistor 29 will again be in the form of a damped half-cycle sine wave and will be of opposite polarity to the preceding half-cycle if caused to flow through primary winding 24 in a reversed direction since all primary windings of the load transformer are wound in the same direction. Thus, a full-cycle partially-damped sine wave is obtained while capacitors 16 and 17 are being charged.

Another full-cycle of output current and power is obtained by consecutively firing the corresponding other two tubes, one being in each pair. First, the tube 3 is fired so that the first capacitor 16 discharges through the path constituted by the primary winding 25 of the loading transformer 27, inductor 20 which is similar to inductor 18, and the tube 3. Then, after this half-cycle is completed, the corresponding tube 4 of the other pair is fired so that the second capacitor 17 is discharged through the path comprising the primary winding 26, inductor 21, which is also equal to inductor 18, and the tube 4, itself.

It is only necessary to properly select the circuit constants so that the first tube 1 is deionizing during the duration of time of charge of the second capacitor 17. This time interval is relatively large compared with the time necessary to completely deionize tube 1. The values of L, C and R may, therefore, be adjusted to give half sine waves of relatively short duration, thereby increasing the output frequency. This is a marked advantage of the apparatus of the present invention.

When steady state operation has been reached, the final voltage across either capacitor 16 or 17 is not the same as that at the end of each initial half-cycle when the circuit is first set in operation. For steady state operation, the final voltages and currents in other parts of the circuit are also different from the initial ones.

Since the operation of the device is mainly concerned with steady state operation, the instantaneous conditions of the principal circuit elements during various parts of a complete cycle of operation will be explained with the aid of the family of curves shown in Fig. 2.

In Fig. 2 are shown voltages to ground at indicated points on Fig. 1. An essential point in obtaining the increase of frequency possible with a four tube inverter as compared to a two tube inverter is that the constants be so selected that the cathode voltage e_{K_1} on tube 1 be maintained positive with respect to the plate voltage e_{P_1} on this tube after tube 1 has conducted and starts to deionize. Likewise, cathode voltages e_{K_2} , e_{K_3} and e_{K_4} must be maintained positive, respectively, with respect to e_{P_2} , e_{P_3} and e_{P_4} after tubes 2, 3 and 4, respectively, have conducted and have started to deionize.

Those conditions will be obtained if

$$2a(1-2d)e^{-\alpha\tau} \sin \phi < e^{-\alpha\tau}(1-d) - d$$

where

$$\phi = \tan^{-1} \frac{1}{a}, d = \frac{E_T}{E_B}, \text{ and } E_T = \text{tube drop}$$

Otherwise, the voltages induced through the transformer back into the cathode and anode circuits will be of sufficient magnitude that the conditions described above do not hold. The values of a and d used in obtaining the curves of Fig. 2 are $a=0.25$ and $d=0.02$. In Fig. 2, five consecutive conducting periods are shown, after

the inverter circuit has reached the steady state voltages of operation. Period 1 is for tube 1 conducting, period 2, for tube 2, etc. Period 5 is a repeat of period 1, for $\omega t = 4\pi$ radians later.

Although the curves of Fig. 2 are largely self-explanatory, some other factors illustrated therein may be pointed out. The charging of capacitor 16 coincides with the appearance of the first half-cycle of output current. This capacitor remains charged while the second capacitor 17 is being charged, causing the generation of the second half-cycle of output current of opposite polarity. The first capacitor 16 then discharges, causing the third half-cycle of output current, the second capacitor remaining charged. The second capacitor then discharges, causing the fourth half-cycle of output current, the first capacitor remaining discharged. After this, the entire operation repeats.

It has already been pointed out that the cathode voltage on any tube must be maintained positive with respect to its anode voltage after a tube has fired and been shut off. This condition must be maintained until the tube has deionized sufficiently so that it will not conduct when the cathode potential is more negative than the anode potential until the grid potential is raised sufficiently positive to trigger the tube. This may be traced for any of the tubes and the potential changes on the other circuit elements may be explained as follows:

First half-cycle: Tube 1 is conducting—other tubes nonconducting.

The capacitor 16 is being charged such that point a is positive.

The anode and cathode potentials e_{P_1} and e_{K_1} rise in a manner corresponding to the charge on the capacitor 16.

The anode of tube 2 is at E_B potential. The potential e_{K_2} on the cathode of tube 2 is highly negative since its potential depends on the charge on capacitor 17 and its potential is still more negative due to potential induced in the primary winding 24 by current flowing in primary winding 23.

The potential e_{P_3} of the anode of tube 3 rises due to rise of potential on capacitor 16 as that capacitor is charged. It is not identical with the potential on the capacitor since part of its potential is due to voltage being induced in primary winding 25 by current flowing in winding 23. The potential e_{P_4} on the anode of tube 4 rises and falls due to potential induced in the primary winding 26 by the current flowing in primary winding 23. Its potential is the algebraic sum of the potential on capacitor 17 and the induced voltage in the winding 26. Where the potential of capacitor 17 is mentioned, there is meant the potential at point a' .

Second half-cycles Tube 2 is conducting, the capacitor 16 remains charged, capacitor 17 is being charged and current flows in primary winding 24.

The potential e_{P_1} on the anode of tube 1 drops to the "B" supply voltage, E_B .

The potential e_{K_1} is now the algebraic sum of the potential on the capacitor 16 and the voltage induced in the primary winding 23 by current flowing in the winding 24.

The potential e_{P_3} is the algebraic sum of the charge on capacitor 16 and the potential induced in winding 25.

The potential e_{P_2} , first of all, drops from E_B to

the same potential as that on capacitor 17, less tube drop, and then rises as the capacitor 17 is charged. It falls to E_B as this half-cycle ends.

5 The cathode potential e_{K_2} also rises as capacitor 17 is charged, its potential differing from that on the capacitor by the voltage induced in primary winding 24.

10 The plate potential e_{P_4} also rises as capacitor 17 is being charged but is not identical therewith because of the voltage induced in primary winding 26.

15 *Third half-cycle:* Tube 3 is conducting, the first capacitor 16 is discharging, the second capacitor 17 remains charged, and current flows in the primary winding 25.

e_{P_1} remains at E_B potential.

e_{K_1} drops because capacitor 16 is discharging but is not identical with potential at point a because of induced voltage in primary winding 23. e_{P_2} drops to and remains at E_B potential and differs from the voltage on capacitor 17 by the voltage induced in primary winding 25.

25 e_{K_2} is the algebraic sum of the charge on the second capacitor 17 and the induced voltage in the primary winding 24.

20 e_{P_3} drops to a potential almost equal to ground potential, being above ground only by the amount of the potential drop in the tube 3.

25 e_{P_4} is the algebraic sum of the potential on the second capacitor 17 and the induced voltage in the primary winding 26. Its wave form is opposite to that of e_{K_2} because the voltages are induced in opposite directions in the windings 24 and 26.

30 *Fourth half-cycle:* Tube 4 is conducting, the first capacitor 16 remains discharged, the second capacitor 17 is discharging, and current flows in the primary winding 26.

35 e_{K_1} is the algebraic sum of the potential on capacitor 16 and the voltage induced in the primary winding 23.

e_{P_1} remains at E_B potential.

e_{K_2} drops due to discharge of capacitor 17 but the potential differs from that on the capacitor due to voltage induced in primary winding 24.

40 e_{P_2} remains at E_B potential.

45 e_{P_3} first drops to the potential of capacitor 16 but throughout this half-cycle its potential is equal to the algebraic sum of the potential on capacitor 16 and the voltage induced in primary winding 25.

50 e_{P_4} drops almost to ground potential, remaining above it only by the amount of potential drop in tube 4.

55 Throughout the operation, cathode potentials e_{K_3} and e_{K_4} remain at ground since the cathodes of tubes 3 and 4 are grounded.

60 It will be noted that the potentials of the elements of the circuit associated with tubes 1 and 2 vary in a similar manner although separated by one-half cycle, while the potentials of the circuit elements of tubes 3 and 4 are also similar to each other in their variation.

65 An example of the selection of suitable circuit constants for a four tube circuit will now be given.

Example

As a complete example of the selection of the circuit constants, take the values of $E_B = 500$, $a = 0.25$ ($m = .456$) and $d = .02$ as limiting the peak forward or inverse voltage E_{P_1} between the plate and cathode of tube V_3 (or plate and cathode of V_4) to approximately 1200 volts. The relation

7
between the peak inverse voltage E obtained and the plate supply voltage is

$$E_B = \frac{E_{FI}}{\Delta(1+2e^{-a\phi} \cos \phi)} = \lambda E_{FI}$$

where

$$\phi = \tan^{-1} \frac{1}{a} \text{ and } \lambda = \frac{1}{\Delta(1+2e^{-a\phi} \cos \phi)}$$

The relation between λ and a may be plotted from the following data for $d=0.02$.

$$\begin{array}{cccc} a & .15 & .2 & .25 & .3 \\ \lambda & .316 & .373 & .420 & .457 \end{array}$$

Thus E_B for $a=0.25$ and an approximately limiting peak inverse or forward voltage of 1200 volts, the highest plate supply voltage permissible would be

$$E_B = \lambda E_{FI} = 0.42(1200) = 504 \text{ volts}$$

The value of a itself was chosen as 0.25 because this value fulfills the condition for high frequency operation that

$$2a(1-2d)e^{-a\phi} \sin \phi < e^{-a\pi}(1-d) - d$$

or

$$0.334 < 0.434 \text{ for } a=0.25 \text{ and } d=0.02$$

If the operating frequency F of 10,000 cycles per second is chosen as being a feasible one and the desired output P selected is 5000 watts, the constants of the circuits may now be determined.

Thus

$$C = \frac{P}{E_B^2 \Delta^2 (1-m^2) F}$$

$$\Delta = \frac{1-2d}{1-m} = \frac{1-2(0.02)}{1-e^{-a\pi}} = \frac{0.96}{1-E^{25\pi}} = \frac{0.96}{1-.456} = 1.765$$

or

$$C = \frac{5000}{(500)(1.765)[1-(.456)^2]10,000} =$$

$$0.81(10^{-6}) \text{ farad} = 0.81 \text{ microfarad}$$

Hence, each capacitor is 0.81 microfarad each working half of the time delivering power through the transformer to the load R .

The inductance L , obtained from previously given relations is

$$L = \frac{0.0253}{F^2 C (1+a^2)} = \frac{0.0253}{10^8 (0.81) 10^{-6} (1+0.0625)} =$$

$$294(10^{-6}) \text{ henries} = 0.294 \text{ millihenry}$$

The load resistance R obtained also from previously given relations is

$$R = \frac{0.318a}{FC(1+a^2)} = \frac{0.318(0.25)}{10^4 (0.81) 10^{-6} (1+0.0625)} = 9.23 \text{ ohms}$$

R is the resistance for the conditions that all transformer windings have the same number of turns and that all reactors, the plate voltage supply and the transformer are lossless. Actually, the external value of R_L would be reduced to make the total resistance effective in each mesh have the value R .

The effective value of the output current I_{eff} into the load is given by

$$I_{eff} = \frac{2a\Delta E_B}{R} \sqrt{\frac{1-E^{-2a\pi}}{4\pi a(1+a^2)}} =$$

$$\frac{2(0.25)1.765(500)}{9.23} \sqrt{\frac{1-(.456)^2}{4\pi(.25)(1.0625)}} = 23.78 \text{ amperes}$$

As a check, the power P should be equal to $I_{eff}^2 R$.
 $I_{eff}^2 R = (23.78)^2 9.23 = 5000 \text{ watts: check.}$

Although the embodiment illustrated in Fig. 11

is for a four tube inverter circuit, it will be apparent that the present invention applies equally well to a circuit utilizing three or more pairs of tubes. As the number of pairs of tubes is increased, however, the percentage increase in maximum frequency of operation diminishes. Finally, a point will be reached where the added complication and additional cost of operation of the apparatus will not justify the relatively small increase in frequency obtained by adding another pair of tubes.

For purposes of illustrating an embodiment of the invention using six tubes, reference is made to Fig. 3. The principle of operation is the same as in the embodiment utilizing four tubes.

In the six-tube circuit, there are provided three pairs of gas discharge tubes 30 and 33, 31 and 34, and 32 and 35, each tube being provided with similar grid circuits and similar external anode to cathode circuits. Tubes 30, 31 and 32, which are corresponding tubes of each of the three pairs, are provided with similar individual grid bias supplies 36, 37 and 38, respectively. Tubes 33, 34 and 35, the corresponding other tubes of each pair, utilize the common bias supply 39, which is similar to the other three bias supplies. These bias supplies furnish a normally high negative bias to the grids of all tubes except when the tubes are triggered. The positive side of the common bias supply is grounded.

The grid circuits of each of the tubes 31, 32, 33, 34, 35 and 36 are provided with similar grid current limiting resistors 40, 41, 42, 43, 44 and 45, respectively.

The output of the pulser timing unit (not shown) is connected to the grid of each tube through the transformers 46, 47, 48, 49, 50 and 51, respectively. The pulsing operation is exactly the same as in the previously described four-tube circuit.

The cathodes of each of the tubes 30, 31 and 32 are connected to the positive side of the grid bias supplies 36, 37 and 38, respectively. The cathodes of the other tubes 33, 34 and 35 are connected to ground.

In the output circuit of the first pair of tubes 30 and 33, there is provided a common capacitor 52. Similarly, for each of the other pairs of tubes 31 and 34, and 32 and 35, there are provided common capacitors 53 and 54, respectively.

The anode circuit of each of the tubes 30, 31, 32, 33, 34 and 35 is provided with a similar inductor 55, 56, 57, 58, 59 and 60, respectively.

The outputs of the three pairs of tubes appear across a common load resistor 61 and are derived from a load transformer having a single secondary winding 62 and three primary windings 63, 64 and 65. All primary windings are wound in the same direction.

The primary winding 63 is common to the external anode to cathode circuit paths of tubes 30 and 33. The primary winding 64 is common to the external anode to cathode circuit paths of tubes 31 and 34. The primary winding 65 is common to the anode to cathode circuit paths of tubes 32 and 35.

The direct current source or "B" supply 66 has its positive side connected to the anodes of tubes 30, 31 and 32 and has its negative side grounded.

The mode of operation is similar in principle to that described in connection with the four tube circuit. The order of firing of the tubes is 30, 31, 32, 33, 34 and 35 in sequence. First, the tube 30 is fired and the capacitor 52 is charged.

causing a half-cycle of output voltage to appear across the load resistor 61. Next, the tube 31 is triggered, charging the capacitor 53 and causing another half-cycle of voltage of opposite polarity to appear across the load resistor 61. This is followed by the firing of tube 32 charging capacitor 54 and causing the third half-cycle of output voltage to appear across the load resistor. The polarity of each half-cycle is, in all cases, opposite to the one preceding. Next, tubes 33, 34 and 35 are fired in order, discharging each capacitor 52, 53 and 54, respectively. This causes three more half cycles of output voltage to appear across the load resistor.

Because of the correspondingly longer time permitted each tube for deionization, the cycles may be shortened such that the maximum frequency of operation is twice that possible with the four tube circuit.

There has thus been described a type of inverter circuit utilizing any plurality of gas discharge tubes in multiples of two. It has advantages in simplicity of construction and stability of operation not found in previously known circuits designed for similar purposes and provides for greatly increased frequency of operation at high current outputs. For symmetrical output, the values of corresponding elements in the different circuits should be the same. If symmetrical output is not essential, this requirement need not be adhered to.

I claim as my invention.

In an apparatus for inverting direct current to alternating current, a source of direct current, means for connecting said source to a plurality of gas discharge tubes, said plurality being an

even number more than two, external anode to cathode discharge circuit paths for each of said tubes, a capacitor common to the discharge circuits of each two of said tubes, means for coupling said discharge circuits to a common load circuit, said coupling means comprising a transformer having a plurality of primary windings each of which is connected in at least one of said discharge circuits, and including a single secondary winding connected in said load circuit, means for triggering said tubes such that said capacitors are charged and discharged in a predetermined consecutive order from said direct current source, means for halting current flow through a tube before the next tube to be fired is triggered, and means for maintaining each tube in a state in which it cannot conduct current while the other tube having its anode to cathode circuit connected to the same capacitor is conducting.

CHARLES C. SHUMARD.
